R. H. HIATT

WHEEL RIM

Filed June 24, 1921

UNITED STATES PATENT OFFICE.

ROSCO H. HIATT, OF GREENS FORK, INDIANA.

WHEEL RIM.

Application filed June 24, 1921. Serial No. 480,222.

To all whom it may concern:

Be it known that I, Rosco H. HIATT, a citizen of the United States, residing in the town of Greens Fork, in the county of Wayne, State of Indiana, have invented a new and useful Construction for Wheel Rims, of which the following is a full, clear, and comprehensive specification, the same being such as will enable others to make and use the same with exactitude.

The object of this invention, broadly speaking, is to provide a detachable wheel rim which will be strong and durable in construction, positive in action, easily operated and controlled, and which can be manufactured and sold at a comparatively low price.

More specifically stated, my object is to provide a detachable wheel rim having means for opening the ends, for closing the ends together, and for locking the ends in closed position, the same being comparatively easy of operation and without need of pounding the parts in removing or replacing the tire, and which will require no other tools for its operation or manipulation.

Other minor and particular objects will suggest themselves in the course of the following description, and that which is new will be correlated in the appended claim.

The preferred means for carrying out my invention in a practical and an efficient manner is shown in the accompanying drawings forming a part of this specification, in which—Figure 1 is a side elevation of a complete rim in which my invention is incorporated, the same being in closed or operative position, Figure 2 is an exterior plan view of a portion of the rim, showing the parts in proximity of the joint. Figure 3 is an inside or interior view of the same in open position. Figure 4 is a longitudinal section, as taken on the line 4—4 of Fig. 3, but with the parts shifted to show the rim in open or inoperative position. Figure 5 is a perspective view of the shifting lever and the parts thereof. And Fig. 6 is an inside view of the device in closed position.

Similar indices denote like parts throughout the several views.

In order that the construction, the operation, and the advantages of my invention may be fully understood and appreciated,

I will now take up a detailed description, in which I will set forth the several features as fully and as comprehensively as I may.

The invention comprises a channeled rim, which is normally round, longitudinally, the rim being cut diagonally at one point on the line A, thereby forming the two end portions B and C as shown.

Rigidly secured to the inner face of the member B, spaced apart and parallel with each other, and extending over the portion C, that is across the line A, are the two major hinge members 1 and 2. The projecting ends of the members 1 and 2 are integrally connected by the crescent portion 3.

Between the members 1 and 2 the material of the member B is cut away, thereby forming a notch in the end of the member B to permit the link 4 of the lever 5 to turn therein. A pivot 6 extends through the members 1 and 2 and it extends across therebetween and through the link 4 whereby the link 4 may turn thereon. A block 7 is formed integral with the contact face of the link 4 which block exactly fits and closes said notch in the end of the member B.

Secured to the inner face of the member C are the two minor hinge members 8 and 9 which correspond with the members 1 and 2 in size, and they are arranged parallel and in alinement therewith, but they are of less length. A pivot 10 extends through the members 8 and 9 and projects across therebetween, and it also extends through the block 4.

A slot 11 is formed across through the central portion of the member C in the center of which will fit the lug 12 which is formed on the link 4, as is shown in Figs. 4 and 5.

Carried by the projecting end portions of the members 1 and 2 are the respective lugs 13 and 14 which also may fit in the slot 11 but located on each side of the lug 12, as shown in Fig. 2.

Formed on the lever 5 is a small lug 15 which may fit in the aperture 16 of the part B, however the lug 15 is not an essential element except when it is employed in place of the lugs 12, 13 and 14, being merely an alternative therefor.

The parts being constructed and assembled substantially as set forth I will presume that the device is in its inoperative or

closed position, as in Figs. 3 and 4, in which position it may be placed in position with relation to a tire to be carried thereby. Now all one has to do to secure the rim to 5 the tire is to grasp the lever 5 and swing it centerward upon its pivot 6, this operation will manifestly move the members B and C endwise apart and in opposite directions with relation to each other, and as the lever 10 5 approaches the member B, with which it will nest as in Fig. 1, it is apparent that the ends of the members B and C will be brought into abutting contact with each other. Also the lugs 12, 13 and 14 will enter and fill the slot 11, and the block 7 will 15 fill the notch in the end of the member B, which will securely lock the members B and C, and the normal expansive spring of the rim will securely hold the lever 5 flat 20 against the member B, as in Fig. 1.

Desiring to remove the tire from the rim one has only to swing the lever 5 from the position in which it is shown in Fig. 1 to the position in which it is shown in Fig. 4, 25 which of course will decrease the diameter of the rim whereby it will be free from the tire.

By the above it will be seen that I provide means for expanding and contracting the 30 rim, and means for locking the rim in its expanded position.

I desire that it be understood that various changes may be made in the several details of construction from that shown and 35 described without departing from the spirit of the invention and without sacrificing any of the advantages thereof which are new and useful and which involve invention.

Having now fully shown and described 40 my invention, what I claim and desire to secure by Letters Patent of the United States, is—

A detachable rim cut diagonally at one point forming ends adapted to fit together, 45 two major hinge members secured to the inner face of one end portion of the rim and projecting on to the inner face of the other end portion of the rim, a crescent portion 50 integrally connecting the projecting end portions of said hinge members, the material of the first mentioned end portion of the rim being cut away forming a notch between said members of the hinge, a lever, 55 a link connected with the lever and adapted to operate in said notch, a pivot extending through the hinge members and through said link, a block integral with the face of said link and adapted to fit and close said notch, two minor hinge members secured to the inner face of the second end portion of the rim, a pivot extending through said minor hinge members and through said block, and a lug formed on the link and 60 adapted to fit in a slot formed through the central portion of said second end portion of the rim, all substantially as shown, 65 whereby the operation of said lever will move the ends of the rim with relation to each other.

In testimony whereof I have hereunto 70 subscribed my name to this specification in the presence of two subscribing witnesses.

ROSCO H. HIATT.
